UNITED STATES PATENT OFFICE.

WILLIAM J. BRASS, OF FENTON, IOWA.

SELF-EXTINGUISHING LAMP.

Application filed March 30, 1920. Serial No. 369,891.

To all whom it may concern:

Be it known that I, WILLIAM J. BRASS, a citizen of the United States, residing at Fenton, in the county of Kossuth and State 5 of Iowa, have invented certain new and useful Improvements in Self-Extinguishing Lamps; and I do hereby declare the following to be a full, clear, and exact description of the invention, such as will enable others 10 skilled in the art to which it appertains to make and use the same.

This invention relates to new and useful improvements in self-extinguishing lamps and has for its primary object the provision 15 of a device of the character stated which is especially adaptable for use by a person when retiring and going to sleep and which will give the person sufficient time to become asleep before the flame of the lamp is 20 automatically extinguished.

A further object of this invention is the provision of a thermostat which is gradually affected by the heat from the flame of the lamp to release a spring actuated element for 25 extinguishing the flame in a given length of time.

A further object of this invention is the provision of a self-extinguishing lamp of the above stated character, which shall be 30 simple, durable and efficient, and which may be manufactured and sold at a comparatively low cost.

With these and other objects in view as will become more apparent as the description 35 proceeds, the invention consists in certain novel features of construction, combination, and arrangement of parts as will be herein-after more fully described and claimed.

For a complete understanding of my invention, reference is to be had to the following description and accompanying drawings, in which:—

Figure 1 is a side elevation, illustrating a lamp extinguisher constructed in accordance with my invention and having the burner cap swung to an open position,

Figure 2 is a side elevation, illustrating the device in non-extinguishing position.

Figure 3 is a top plan view of the device, 50 Figure 4 is a longitudinal sectional view illustrating the adjustment of the thermostat.

Figure 5 is a perspective view illustrating the trip element,

55 Figure 6 is a similar view illustrating an extinguishing element,

Figure 7 is a similar view illustrating a ratchet element.

Referring in detail to the drawings, the numeral 1 indicates as an entirety a lamp 60 burner including a body portion 2 provided with the usual screw threaded neck 3 adapted to be threaded into the bowl of a lamp (not shown). A cap 4 is hinged to the body 2 and is adapted to be swung over a wick tube 65 5 having the usual wick 6 therein. The foregoing description relates to a well known construction of lamp burner and to which my invention is applied.

An extinguishing element 7 consists of an 70 angle shaped plate 8 provided with legs 9 that are journaled on pins 10 secured to the sides of the wick tube. A spring 11 is secured to one of the pins 10 and to one of the legs 9 for normally urging the extinguishing element 7 over the wick tube and its wick for the purpose of extinguishing the flame thereon. A flexible supporting rod 12 is secured to the body 2 adjacent the wick tube and supports a thermostat 13 adjacent 75 80 to the upper end of the wick tube and wick so that the heat from the flame on the wick will gradually affect the thermostat. A bracket 14 is secured to the body 2 under the thermostat 13 and has hinged thereto a 85 trip element 15 provided with a tongue 16. The thermostat 13 is in the form of a receptacle 17 which is adapted to be partially filled with alcohol or similar fluid which will, when heated, cause said casing to expand. A pin 18 is secured to the casing 17 and engages the trip element 15. The walls of the casing 17 are capable of flexing according to the expansion and contraction of the fluid within said receptacle for the purpose of actuating the trip 15. 90 95

One of the pins 10 is provided with a vertical extension 19 on which is journaled a latch arm 20 having a tongue 21 formed on one end adapted to engage one of the legs 9 100 of the extinguishing element 7 for holding the same away from the wick and wick tube and against the tension of the spring 11. A tongue 22 is formed on the other end of the latch member 20 and is adapted to abut the 105 tongue 16 of the trip element 15 so that when said trip element 15 is affected by the thermostat 13, it disengages the tongues 16 and 22 and permits the tongue 21 to move away from the extinguishing element under 110 the influence of the spring 24, or in other words the latch member 20 swings on the ver-

tical extension 19 freeing the tongue 21 from the extinguishing element 7 which is forced over the wick and wick tube by the spring 11 to extinguish the flame.

5 From the foregoing description taken in connection with the accompanying drawings, it will be noted that the action of the thermostat 13 is gradual and requires a given period of time before the fluid therein has 10 been expanded sufficiently to disengage the trip 15 from the latch member 22.

A rod 25 is connected to the flexible supporting element 12 and is adjustably connected to a bracket 26 by nuts 27 so that the 15 location of the thermostat 13 in respect to the trip element 15 can be varied for the purpose of lengthening and shortening the time required to actuate the device by the heat from the flame of the lamp.

20 Having thus described my invention, what I claim is:

1. A flame extinguishing means comprising an extinguisher, means to urge it into extinguishing position, a laterally movable 25 detent to normally prevent movement of the extinguisher, means tensioned to retract the detent to release said extinguisher, a lever to normally abut the detent to prevent retraction thereof, and a thermostatic means

operable by the flame and through rise in 30 the temperature thereof to shift the lever to release the detent.

2. A flame extinguishing means comprising an extinguisher, a thermostat to be heated by the flame, means suspending the 35 thermostat for lateral adjustment relatively to the flame to control the time interval before extinction of the flame, mechanism to clamp said means in adjusted position, trip means operable to release the extinguisher 40 controlled by the operation of the thermostat through rise in the temperature thereof, including a lever for vertical tilting through expansion of the thermostat directly, a laterally movable lever to abut the first lever, 45 said tilting movement serving to move the first lever out of the path of movement of the second lever to release the latter, a spring to urge the levers into contact and displacement of the second mentioned lever, 50 and said second lever being adapted to overlap and serve as a detent for the extinguisher.

In testimony whereof I affix my signature in presence of two witnesses.

WILLIAM J. BRASS.

Witnesses:

F. H. BOHN,
F. C. BAILEY.
